MEANS FOR REMOVING ICE CUBES FROM
REFRIGERATOR TRAYS

Henry L. White, Red Bluff, Calif.

Application February 16, 1931, Serial No. 516,242

13 Claims. (Cl. 62—108.5)

This invention relates generally to a method and means for releasing and facilitating the removal of ice cubes from refrigerator trays, and particularly to an attachment for such a tray employing electrical heating elements incorporated in the walls of the tray, whereby to thaw the cubes at their points of contact with the walls of the tray, to enable the removal of the cubes by gravity upon the inversion of the tray.

It is an object of this invention to provide a new and novel application of electrical heating energy to the general purpose of thawing ice free from its container, or the vessel in which it has been manufactured, so as to facilitate the removal of the ice therefrom, and to permit the ice to be gravitationally removed from its container.

These and other objects of the invention, its nature and its composition and arrangement and combination of parts will be readily understood by any one acquainted with the art to which this invention relates upon consulting the following descriptions of the drawings, in which:—

Figure 1 is a top plan view of an ice cube tray having electrical heating elements associated therewith.

Figure 2 is a side elevational view of Figure 1.

Figure 3 is a transverse vertical cross sectional view taken approximately on the line 3—3 of Figure 1.

Figure 4 is a view similar to Figure 3 showing the exterior casing removed from the tray.

Figure 5 is a transverse vertical cross sectional view of another form of my invention employing instead of cylindrical or wire heating elements, a ribbon heating element disposed in the walls and in the central partition of or the grid of the tray.

Referring in detail to the drawings the numeral 5 generally designates an ice cube freezing tray which may be of any conventional type such as that employed in mechanical or artificial ice machines either of the domestic type or of the commercial type. It is to be understood that the invention is not limited to freezing trays of mechanical or other ice making machines, but is to be applied to any container of ice, the ice either being made or manufactured in the said container or not as the case may be. The broad idea of the invention is the provision of electrical heating means for heating the walls of a container for thawing the ice next to the walls of the container so as to free the ice from gripping the container to permit it to be easily removed therefrom.

The form of ice cube tray illustrated in the

drawings is of well known conventional type and is employed simply to facilitate the illustration of the invention. It comprises a grid 6 disposed within an inside casing 7, and either formed integrally therewith, attached thereto, or unattached thereto as in the case of certain well known types of refrigerator trays. Reference will now be had to Figures 1 to 4, inclusive.

At one end of the tray and secured upon the outside of the casing 7 is a suitable electrical connection plug 9 to which is adapted to be connected any suitable electric current supply means such as a household electrical connection cord. Tubes 10 are disposed in horizontal positions and mounted on the outside of the side and end walls 15 of the inner casing 7 at a height slightly above the intermediate height thereof, and a suitable cylindrical heating element 11 is disposed therein. The tube or tubes 10 is secured as indicated at 12 in any suitable manner to the exterior of the inner casing 7. Similar tubes 13 are secured as indicated at 14 approximately on the meeting point of the lower edge of the side walls of the inner casing 7 and the bottom thereof, and the tube 13 surrounds the tray at this point. The tube 13 contains also a suitable cylindrical heating element 15. Another similar tube 16 is secured as indicated at 17 centrally and longitudinally of the underside of the bottom 18 of the inner casing 7, and is extended to join the portions of the tubes 13 which are at either end of the tray. A short vertical tube 19 rises from the juncture of the tubes 13 and 16 at the end of the casing having the connection plug 9, and is attached to the outside of the inner casing, and communicates with the inner end of the connection plug 9. The heating elements are suitably connected to the plug 9. Reference has been had thus far chiefly to Figure 4. It will be observed that Figure 3, while disclosing an identical arrangement of cylindrical heating elements 20, 21 and 22, has a specifically different method of mounting the heating element tubes to the outside of the inner casing. In the case of the form shown in Figure 3, the interior casing 7a and the exterior casing 8a are preferably formed continuously in one piece, the exterior casing 8a being suitable stamped or formed to provide the open tubular formations 23, 24 and 25 corresponding to the tubes 10, 13 and 16, whereby to confine the heating elements mentioned in the same position as obtains in the case of the form illustrated in Figure 4. Another noticeable difference is that at the point 26 in Figure 3 the inner casing is upwardly swelled to accommodate

the cylindrical heating element 22, whereas in Figure 4 no such swelling is found. Of course, an exterior casing 8 separate from the interior casing 7 but of exactly the form of the exterior casing 8a is adapted to be placed outside of the inner casing 7, to achieve the general arrangement shown in Figure 3, namely, an interior and an exterior casing closely associated to provide the body of the tray and to support and confine the heating elements. The exterior appearances of the forms illustrated in Figures 3 and 4 are practically the same.

Referring to Figure 5, wherein a further form of the invention is disclosed, it will be apparent that the inner casing 7b and the outer casing 8b are so formed and attached together that there is provided therebetween a space wherein is confined a ribbon heating element 27 which may be of any suitable form, to extend in a flat 20 and extended manner throughout the space between the inner and the outer casings 7b and 8b, respectively. The grid 6a rises in the same point of disposition as the grid 6 of the other forms of the invention. It is formed integral 25 with the interior casing and provided with a vertical and longitudinally extended space which rises to a point just within the tip of the upper extremity of the grid, and in which is confined a ribbon heating element 28 connected with the 30 heating element 27 at the point 29.

The interior and exterior casings may be of any suitable material and may be of tubular formation for confining the heating elements, and any suitable electrical circuit may be employed 35 whereby to energize the heating elements, and a suitable control means may be associated with the circuit to prevent the overheating of the device.

Thus it is believed that I have provided a new 40 utilization for electrical heating elements, namely that of applying electrically generated heat to the container of a body or bodies of ice whereby to facilitate the removal of the ice therefrom by thawing the surfaces of the ice in contact with 45 and gripping the interior surfaces of the container.

In the case of ordinary ice cube trays, it is necessary to carry the dish or tray of cubes from the refrigerator to the sink and run over the 50 inverted tray hot water or cold water, the operation being attended with various inconveniences which are well known, and which result in loss of ice, unsanitary handling of the ice and other inconvenient and undesirable conditions. However, when using my invention, it is necessary only to connect the plug 9 with a suitable current outlet such as would be conveniently found in a room of a house or apartment, and in ten or fifteen seconds or thereabouts, the ice cubes have been conditioned to be easily removed from the tray simply by inverting the tray over the provided receptacle provided for receiving the loosened cubes, whereupon the cubes will drop out of the tray, 65 without handling, and without breakage or waste, and in a manner and at a saving of time which will be found highly desirable, especially since the device of my invention may be incorporated in a ice box or refrigerator which constitutes 70 part of a complete unit of refrigerator and cube remover, so that the cubes may be quickly and conveniently removed from the tray at the ice box or refrigerator rather than at some other place removed therefrom.

It is to be definitely understood that I do not

desire to limit the application of this invention to the particular modifications set out herein to illustrate the principles thereof, and any change or changes may be made in material, arrangement and combination of parts consistent with 5 the spirit of the invention and the scope of the subjoined claims.

What is claimed is:—

1. An ice cube freezing tray comprising an inner tray form, electrical heating means supported at the outside of the walls of the tray form, an outer tray form surrounding and connected to the inner tray form and having tubular portions enclosing the heating means, and other heating means supported at the outside of the 15 juncture of the lower edge of the walls and of the bottom of the inner tray form, said outer tray having second tubular portions enclosing and supporting said other heating means.

2. An ice cube freezing tray comprising an 20 inner shell, an outer shell conformed to and secured to the inner shell, outwardly expanded portions formed in the outer shell defining with the inner shell heating element receiving chambers, and electrical heating elements in the 25 chambers, some of said chambers being arranged longitudinally of the tray and spaced from the upper and lower edges of the walls thereof, others of said chambers being arranged at the junctures of the lower edge of the walls 30 with the side edges of the bottom of the tray.

3. An ice cube freezing tray comprising an inner shell including a grid having a central longitudinal partition, an outer shell conformed to 35 and secured to the inner shell, outwardly expanded portions formed in the outer shell defining with the inner shell heating element receiving chambers, and electrical heating elements in the chambers, some of said chambers being arranged longitudinally of the tray and 40 spaced from the upper and lower edges of the walls thereof, others of said chambers being arranged at the junctures of the lower edge of the walls with the side edges of the bottom of the tray, and one of said chambers located longitudinally of the bottom of the tray and spaced 45 from the side edges thereof and under the said central longitudinal partition.

4. An ice cube freezing tray comprising an inner shell including a grid having a central longitudinal partition, an outer shell conformed to 50 the outside of and secured to the inner shell, outwardly expanded longitudinally extending portions formed in the outer shell defining with the inner shell tubular heating element receiving chambers, an electrical heating element supported in each of the chambers, said electrical heating elements being supported solely by the walls of the chambers, some of said chambers being near to the top of said walls and others of 55 said chambers being near to the bottom of said walls.

5. An ice cube freezing tray comprising an inner shell including a grid having a central longitudinal partition, an outer shell conformed to 60 and secured to the inner shell, outwardly expanded portions formed in the outer shell defining with the inner shell heating element receiving chambers, and electrical heating elements in the chambers, some of said chambers being arranged longitudinally of the tray and spaced 65 from the upper and lower edges of the walls thereof, others of said chambers being arranged at the junctures of the lower edge of the walls with the side edges of the bottom of the tray, and 70

one of said chambers being located longitudinally of the bottom of the tray and spaced from the side edges thereof and under the said central longitudinal partition, said one of said chambers having its ends connected to said other chambers.

6. An ice cube freezing tray comprising an inner shell including a grid having a central longitudinal partition, an outer shell conformed to and secured to the inner shell, outwardly expanded portions formed in the outer shell defining with the inner shell heating element receiving chambers, and electrical heating elements in the chambers, some of said chambers being arranged longitudinally of the tray and spaced from the upper and lower edges of the walls thereof, others of said chambers being arranged at the junctures of the lower edge of the walls with the side edges of the bottom of the tray, and one of said chambers being located longitudinally of the bottom of said tray and spaced from the side edges thereof and under the said central longitudinal partition, said one of said chambers having its ends connected to said other chambers, a connection plug on one end of the tray, a vertical chamber at the same end of the tray and with which all of the chambers communicate, said vertical chamber being communicated with the connection plug.
7. In an ice cube forming tray including a bottom and side and end walls rising therefrom, a grid resting on and connected to the bottom, said grid including a central longitudinal partition and a plurality of transverse partitions intersecting said central partition, said bottom, end walls, and side walls having laterally outwardly extending chamber means and electrical heating element means extending along and contained by said chamber means, at least one of said chamber means extending along and in heat exchange relation to said central partition.
8. In an ice cube forming tray including a bottom and side and end walls rising therefrom, a grid resting on and connected to the bottom, said grid including a central longitudinal partition and a plurality of transverse partitions intersecting said central partition, said bottom, end walls, and side walls having outwardly spaced portions which with the exterior thereof define electrical heating element enclosures, and electrical heating element means extending in and contained by said enclosures, one of said enclosures being located at the juncture of the lower end of said central partition and said bottom.
9. In an ice cube forming tray including a bottom and side and end walls rising therefrom, a grid resting on and connected to the bottom, said grid including a central longitudinal partition and a plurality of transverse partitions intersecting said central partition, said bottom, end walls, and side walls having outwardly spaced portions which with the exterior thereof define

electrical heating element enclosures, and electrical heating element means extending in and contained by said enclosures, some of said enclosures being located at the junctures of the lower ends of said side and said end walls with said bottom.

10. In an ice cube forming tray including a bottom and side and end walls rising therefrom, a grid resting on and connected to the bottom, said grid including a central longitudinal partition and a plurality of transverse partitions intersecting said central partition, said bottom, end walls, and side walls having outwardly spaced portions which with the exterior thereof define electrical heating element enclosures, and electrical heating element means extending in and contained by said enclosures, one of said enclosures being located at the juncture of the lower end of said central partition and said bottom, some of said enclosures being located at the junctures of the lower ends of said side and said end walls with said bottom.

11. In an ice cube forming tray including a bottom and side and end walls rising therefrom, a grid resting on and connected to the bottom, said grid including a central longitudinal partition and a plurality of transverse partitions intersecting said central partition, said bottom, end walls, and side walls having outwardly spaced portions which with the exterior thereof define electrical heating element enclosures, and electrical heating element means extending in and contained by said enclosures, some of said enclosures being located at the junctures of the lower ends of said side and said end walls with said bottom, and others of said enclosures being located longitudinally along said side walls and of said end walls of the tray and intermediate the upper and lower ends thereof.

12. An ice cube freezing tray comprising a wall involving an inner shell, a conforming outer shell secured on the exterior of said inner shell, said outer shell being laterally outwardly deformed away from said inner shell so as to define longitudinal substantially semi-circular cross section chambers, and electrical heating elements supported in said chambers, some of said chambers being spaced from the upper and lower edges of the wall of the tray.

13. An ice cube forming tray comprising a bottom, side walls and end walls, a grid lying within said side and end walls and secured to said bottom, said grid including a central longitudinal partition and a plurality of transverse partitions intersecting said central partition, said bottom and said side and end walls having laterally outwardly extending tubular enlargements defining heating element chambers, and electrical heating elements contained by said chambers.

HENRY L. WHITE.
